CLAIM

[51] LOC (6) Cl. 03-01

The ornamental design for tear-drop side pockets for a golf bag, as shown and described.

[52] U.S. Cl. D3/255

DESCRIPTION

[58] Field of Search D3/255, 259; 206/315.2, 206/315.3, 315.4, 315.5, 315.6, 315.7, 315.8; 224/917, 918

FIG. 1 is a front elevational view of a tear drop side pocket for a golf bag showing my new design; and, FIG. 2 is a front elevational view of the second tear drop side pocket for a golf bag.

[56] References Cited

The broken line showing of a golf bag in FIGS. 1 and 2 is for illustrative purposes only and forms no part of the claimed design.
